METHOD FOR PRODUCING ALKYL ESTERS
OF HIGHER FATTY ACIDS

Frederick H. Gayer and Charles E. Fawkes, Chicago, Ill., assignors to Continental Research Corporation, Chicago Heights, Ill., a corporation of Illinois

No Drawing. Application January 21, 1942,
Serial No. 427,536

14 Claims. (Cl. 260—97.5)

1

This invention relates to an improved method for producing alkyl esters of higher fatty acids, and particularly to the esterification of fatty acids in mixtures thereof with resin acids, and is a continuation-in-part of our copending application Serial No. 284,915, filed, July 17, 1939.

Our improved method is especially useful as a preliminary step in processes for the separation of the constituents of organic mixtures containing both fatty and resin acids, as for example tall oil. Such processes are set forth in our Patent No. 2,166,812 and in the following copending applications: Serial Nos. 284,917, now Patent No. 2,288,946, and 284,918, now Patent No. 2,288,947, both filed July 17, 1939. These processes comprise esterification of the fatty acids, transforming the resin acids into resinates, and separating the esters from the resinates. The present application discloses a method whereby the fatty acids can be quantitatively esterified in such a way that the esterification reaction is sharply restricted to the fatty acids and does not at all extend to the resin acids.

Esterification of the fatty acids is usually accomplished by reacting the mixture with an excess of an alcohol in the presence of a catalyst. Due to the greater reactivity of the fatty acids esterification is restricted to the fatty acids if the catalyst concentration is kept within certain limits. This forms the basis for present methods for the quantitative determination of fatty and resin acids. The esterification reaction, however, ceases to be selective toward the fatty acids and will be extended to the resin acids if the catalyst concentration is materially increased (Patent No. 1,829,481).

Numerous catalysts for the esterification reaction have been described in the literature and in patents. By far the most active catalysts are strong acids such as hydrochloric or sulfuric. They have the disadvantage that their action on the equipment is rather destructive and that they cause discoloration of the reaction product. Sulfonic acids have a milder action on the equipment but also cause discoloration. Anhydrous metallic chlorides and sulfates, metallic soaps and finely divided metals also have been recommended as catalysts. They are much less active catalysts than mineral acids. All catalysts have the added disadvantage in common that they must be removed after the reaction has proceeded to the desired point, which means an additional operation.

Considering the disadvantages connected with the use of catalysts, a process whereby esterifica-

2

tion could be effected without the use of a catalyst, would be of great practical value. The present application discloses such a process.

Briefly our process comprises subjecting a mixture of tall oil and a monohydric aliphatic alcohol, in the absence of a catalyst, to treatment under pressure by heating to a suitable temperature and discontinuing such treatment at a point where the fatty acids are completely esterified and at which point esterification of the resin acids has not yet begun. The important elements entering into our process are: The kind of alcohol used, the quantity of alcohol used, the time required for the treatment and the temperature at which the treatment is effected.

The alcohols we use in our process are members of the monohydric aliphatic alcohol series and include methyl, ethyl, propyl, butyl, and amyl alcohols and the isomers of the last three alcohols and which are hereinafter, and particularly in the claims termed "low molecular" weight monohydric aliphatic alcohols. The choice of the alcohol depends on the type of fatty acid ester desired as one of the end products. If our object is only the separation of the fatty and resin acid portion of tall oil regardless of the type of esters obtained, we prefer, for simple reasons, the use of methyl alcohol.

The quantity of alcohol we use is always in excess of the calculated quantity required for the esterification of the fatty acids. In calculating the theoretically required quantity of alcohol, we assume the figure of 282 for the average molecular weight of the fatty acids contained in tall oil. For example, 100 parts by weight of a tall oil containing 52% fatty acids will require 5.9 parts of methyl alcohol for the esterification of the fatty acids. In practice we may use from slightly more than the calculated quantity up to 4 or more times that quantity of alcohol. The excess used depends on the particular nature or source of the tall oil treated, different oils requiring different proportions of excess alcohol for esterification in the same period of time. With the same tall oil, the time needed for esterification of its fatty acids is shorter when the proportion of excess alcohol present is higher. For example, in the above tall oil the fatty acids were esterified in 8 hours when using 3.2 times the calculated quantity of methyl alcohol, whereas at the same temperature, 22 hours were required when only 1.35 times the calculated quantity of alcohol was used. After esterification of the fatty acids is complete, the excess of alcohol is removed by distillation. Together with the al-

cohol we also distill off the water formed in the esterification reaction.

The alcohols are preferably used in a rather concentrated form but our process does not require the use of anhydrous alcohols. We have successfully used, for example, methyl alcohol of 80% strength by volume, or the constant boiling mixture of isopropyl alcohol with water which contains only 91% by volume of anhydrous isopropyl alcohol.

The temperature for esterification, according to our process, ranges between the following limits. The lower limit is the temperature at which the mixture of tall oil and alcohol would boil at atmospheric pressure. This corresponds closely to the boiling point of the alcohol used which is 66° C. for methyl alcohol and 140° C. for n-amyl alcohol. The upper limit of temperature is approximately 200° C. The corresponding pressures range from atmospheric to approximately 500 pounds per square inch. Esterification is extremely slow on refluxing a mixture of tall oil and an alcohol in the absence of a catalyst at atmospheric pressure. If, however, the mixture is heated in a closed system to a temperature above its boiling point at atmospheric pressure, the reaction velocity increases as the temperature is raised. We have found that the effect of the temperature on the velocity of the esterification reaction conforms to the general rule according to which a rise of 10° C. approximately doubles the rate of reaction. In the following Table I the velocity of the reaction is expressed as the time required to reduce the initial acid number of 173 of a refined tall oil to the same extent on heating it with four times the theoretical quantity of methyl alcohol in experiments made at different temperatures. With this particular oil, a decrease of 106 points in acid number corresponds to a complete esterification of the fatty acids.

Table I

Tem- per- ture, °C.	Pressure, lbs./in. ² Ga.	Decrease of acid No.	Time required, hrs.	Decrease of acid No.	Time required, hrs.	Decrease of acid No.	Time required, hrs.
72	Atm.	9	6	89	22	106	85
100	50	9	0.5	89	3	106	8
130	120			89	1	106	3.5
146	180						

The foregoing table clearly shows the time element involved, and indicates that with four times the theoretical quantity of methyl alcohol a temperature of approximately 130-140° C. insures a sufficiently high reaction velocity for commercial operation. With lower ratios of excess alcohol the temperature must be correspondingly raised if esterification is to be effected in the same time, and we may use temperatures up to approximately 200° C. Thus within the limits of our invention we can control the time factor by either the temperature or the excess of alcohol used or by both.

While the esterification of resin acids becomes of an important magnitude only at temperatures above 200° C. (Patent No. 1,924,934) we have found that the resin acids may undergo a slow esterification even between the temperature limits of our process. So slow are the resin acids to react, however, that the beginning of their reaction is always preceded by the complete esterification of the fatty acids. We have actually found an inhibition period between the point of the completion of the esterification of the fatty acids and the beginning of the esterification of the resin

acids during which period the acid number stays constant. This inhibition period may be of a duration from about one-half hour to several hours. Its existence enables us to stop the reaction sharply at a point at which the fatty acids are completely esterified and before commencement of esterification of the resin acids. This is an important requirement of the usefulness of our process since our ultimate purpose is to enable a sharp separation of the fatty acid component of tall oil from the resin acids to be made by methods such as those set forth in our aforesaid patent and copending applications.

According to our process, the esterification is effected in a pressure vessel which may be constructed of any metal reasonably corrosion-proof against tall oil, such as stainless steels, Monel metal, aluminum, etc. We charge the tall oil together with an excess of the alcohol into the pressure vessel and raise the temperature to the desired level. The progress of the esterification can be easily followed by withdrawing samples from time to time and, after evaporating the excess alcohol and the water formed during the reaction determining the acid number of the oil. At the point where the fatty acids will be completely esterified, the acid number will be entirely due to the resin acids. The acid number expressing the quantity of resin acids present varies with different oils depending on their resin acid content and has to be determined previously by analytical laboratory methods. When the acid number indicates complete esterification of the fatty acids, the heating is discontinued and the excess alcohol and the water formed in the reaction are removed by distillation, at first at atmospheric pressure and then finished in vacuo. We obtain an esterification mixture of good color, unharmed by side-reactions which are liable to occur in processes in which catalysts are used. The use of pressure

equipment at first appears to be a complication as compared to processes using catalysts at atmospheric pressure. Actually, however, it is a great simplification, since materials can be used for the construction of the pressure equipment which under the influence of active catalysts would disintegrate in a short time. Whatever corrosion action free fatty and resin acids have at higher temperatures on most metals is greatly reduced due to the presence of the alcohol. Instead of using a pressure vessel and working by the batch method, our process may also be carried out in a continuous manner by supplying a mixture of tall oil and alcohol into one end of a reaction chamber kept at a suitable temperature and continuously discharging the reacted mixture at the other end of said reaction chamber.

The following Table II shows the change of the acid number with time for two different tall oils reacted with methyl alcohol. Oil No. 1 was a crude tall oil of acid number 166, containing 55 per cent fatty acids and 38 per cent resin acids. Oil No. 2 was a tall oil refined according to our Patent No. 2,223,850, of acid number 173, con-

taining 57 per cent fatty acids and 37 per cent resin acids. The table clearly indicates the inhibition periods of approximately 1 hour and 1 1/4 hour respectively after which a further slow decrease of the acid number indicates a slow esterification of the resin acids.

Table II

Oil No. 1, reacted at 145° C.			Oil No. 2, reacted at 163° C.		
Time, hours	Acid number	Inhibition period	Time, hours	Acid number	Inhibition period
1	104		1	79	
2 1/2	75		2 1/2	71	
3 1/2	70		3 1/2	68	
4 1/2	70	1	2 1/2	67	
5 1/2	66		3 1/2	67	1 1/4
6 1/2	63		5 1/2	65	

The tall oil we use can be either crude or refined.

Example 1

Five hundred grams of a refined tall oil of acid number 173, containing fatty acids 57 per cent, resin acids 37 per cent and 160 cc. of methyl alcohol are charged into a steel pressure bomb lined with aluminum and equipped with a sampling valve. The bomb is heated in an oil bath which is kept at a constant temperature of 180° C. After 6 hours heating, the acid number of the oil as determined on samples withdrawn, decreases to 68, which figure does not change on further heating for one-half hour. Heating is stopped, the excess methyl alcohol and the water formed distilled off. We obtain five hundred and fifteen grams esterified mixture of good color.

Example 2

200 pounds of a crude tall oil containing 35% resin acids and 50 pounds methyl alcohol were heated in a steel pressure tank under a pressure of 170 pounds. After 13 hours, the acid number was 63 and remained constant for the next 4 hours. The heating was now stopped and the excess alcohol and the water distilled off.

Example 3

250 grams of a crude tall oil containing 42% resin acids and 40 cc. of 80% methyl alcohol by volume were charged into a pressure vessel and heated 23 hours at a temperature of 170-5° C. when the acid number became constant at 78.

Example 4

300 grams of a crude tall oil containing 42% resin acids were treated with 30 cc. methyl alcohol (corresponding to an excess of approximately 50%) at a temperature of 166-170° C., the pressure rising to about 210 pounds. The acid number became constant at 78 after 20 hours heating when the excess methyl alcohol and the water were distilled off.

Example 5

300 grams of a crude tall oil containing 42% resin acids were reacted with 60 cc. isopropyl alcohol containing 9% water at a temperature of 165-170° C. the pressure rising to about 85 pounds. The esterification of the fatty acids was completed in 23 hours when the acid number became constant for one hour at 78.

6
Example 6

300 grams of a crude tall oil containing 42% resin acids were reacted with 65 cc. normally amyl alcohol at a temperature of 167-167° C., the pressure rising up to about 27 pounds. Esterification of the fatty acids was complete in 23 hours.

We claim as our invention:

1. The process of esterifying the fatty acids contained in a tall oil mixture of fatty acids and resin acids, which comprises treating a mixture consisting of said tall oil and an excess of a low molecular weight monohydric aliphatic alcohol, in the absence of a catalyst, at a superatmospheric pressure and a temperature of from about the boiling point of the mixture to approximately 200° C. and discontinuing the reaction as soon as the fatty acids are completely esterified and before esterification of the resin acids begins.
2. The process of esterifying fatty acids contained in tall oil, which comprises heating a mixture consisting of tall oil and a low molecular weight monohydric aliphatic alcohol, in the absence of a catalyst, at a superatmospheric pressure and a temperature of from above that at which the mixture boils at atmospheric pressure and below approximately 200° C. for a period sufficient to effect esterification of only the fatty acids and discontinuing the reaction before esterification of the resin acids occurs.
3. The process of esterifying fatty acids contained in tall oil, which comprises heating a mixture consisting of a tall oil and a low molecular weight monohydric aliphatic alcohol, in the absence of a catalyst, at a superatmospheric pressure and a temperature of from above that at which the mixture boils at atmospheric pressure and below approximately 200° C. for a period sufficient to effect esterification of only the fatty acids, the said alcohol being in molal excess of the fatty acid content of the tall oil and before esterification of the resin acids begins.

4. The process of esterifying fatty acids contained in tall oil, which comprises heating a mixture consisting of a tall oil and a low molecular weight monohydric aliphatic alcohol, in the absence of a catalyst, at a superatmospheric pressure and a temperature of from about the boiling point of the mixture at atmospheric pressure to approximately 200° C. and discontinuing the reaction as soon as the fatty acids are completely esterified and before esterification of the resin acids begins.

5. The process of esterifying fatty acids contained in tall oil, which comprises heating a mixture consisting of a tall oil and an excess of a low molecular weight monohydric aliphatic alcohol, in the absence of a catalyst, at a superatmospheric pressure of from about atmospheric to about 500 pounds per square inch, and at a temperature of from about the boiling point of the mixture at atmospheric pressure to approximately 200° C. and discontinuing the reaction as soon as the fatty acids are completely esterified and before esterification of the resin acids begins.

6. The process of esterifying fatty acids contained in tall oil, which comprises heating a mixture consisting of a tall oil and a low molecular weight monohydric aliphatic alcohol, in the absence of a catalyst, at a superatmospheric pressure and a temperature of from above the boiling point of the mixture at atmospheric pressure to approximately 200° C. and discontinuing the reaction as soon as the fatty acids are completely esterified and before the esterification of the tall oil resin acid content begins.

7. The process of esterifying fatty acids contained in tall oil, which comprises reacting a mixture consisting of tall oil and an excess of a low molecular weight monohydric aliphatic alcohol, in the absence of a catalyst, at a superatmospheric pressure and a temperature of from above the boiling point of the mixture at atmospheric pressure to approximately 200° C. and discontinuing the reaction as soon as the acid number of the tall oil becomes constant and before esterification of the resin acids begins.

8. The process of esterifying fatty acids contained in tall oil, which comprises reacting a mixture consisting of a tall oil and an excess of a low molecular weight monohydric aliphatic alcohol, in the absence of a catalyst, at a superatmospheric pressure and a temperature of from above the boiling point of the mixture at atmospheric pressure to approximately 200° C. and discontinuing the reaction as soon as the acid number of the tall oil becomes constant for at least one hour and before esterification of the resin acids begins.

9. The process of esterifying fatty acids contained in tall oil, which comprises reacting a mixture consisting of a tall oil and an excess of a methyl alcohol, in the absence of a catalyst, at a superatmospheric pressure and a temperature of from above the boiling point of the mixture at atmospheric pressure to not in excess of approximately 200° C. and discontinuing the reaction as soon as the fatty acids are esterified and before esterification of the resin acids begins.

10. The process of esterifying fatty acids contained in tall oil, which comprises reacting a mixture consisting of a tall oil and an excess of an ethyl alcohol, in the absence of a catalyst, at a superatmospheric pressure and a temperature of from above the boiling point of the mixture at atmospheric pressure to not in excess of approximately 200° C. and discontinuing the reaction as soon as the fatty acids are esterified and before esterification of the resin acids begins.

11. The process of esterifying fatty acids contained in tall oil, which comprises reacting a mixture consisting of a tall oil and an excess of

5 an iso-propyl alcohol, in the absence of a catalyst, at a superatmospheric pressure and a temperature of from above the boiling point of the mixture at atmospheric pressure to not in excess of approximately 200° C. and discontinuing the reaction as soon as the fatty acids are esterified and before esterification of the resin acids begins.

10 12. In a process for separating the fatty acid and resin acid constituents of tall oil, the step of esterifying the fatty acids, which consists in reacting a mixture of a tall oil with a monohydric aliphatic alcohol, in the absence of a catalyst, at a superatmospheric pressure and a temperature of from above the boiling point of the mixture at atmospheric pressure to approximately 200° C. and discontinuing the reaction after the fatty acids are completely esterified and before esterification of the resin acids begins.

15 13. In a process for producing fatty acid esters from fatty acids contained in a tall oil in admixture with resin acids, the step which consists in reacting said mixture with a low molecular weight monohydric aliphatic alcohol, in the absence of a catalyst, at a superatmospheric pressure and a temperature of from above the boiling point of the mixture at atmospheric pressure to approximately 200° C. and discontinuing the reaction after the fatty acids are completely esterified and before esterification of the resin acids begins.

20 14. The process of producing a mixture of fatty acid esters and resin acids, which comprises treating a mixture consisting of a tall oil and a low molecular weight monohydric aliphatic alcohol, in the absence of a catalyst, at a superatmospheric pressure and at a temperature of from above the boiling point of the mixture at atmospheric pressure not in excess of approximately 200° C., discontinuing the reaction as soon as the fatty acids are completely esterified and before esterification of the resin acids begins, and removing the excess of alcohol and water formed during the reaction.
